UNITED STATES PATENT OFFICE.

HENRY E. VAN NESS, OF ELMIRA, NEW YORK.

YARN CLEANER.

Application filed June 8, 1922. Serial No. 566,721.

To all whom it may concern:

Be it known that I, HENRY E. VAN NESS, a citizen of the United States, residing at Elmira, in the county of Chemung and State 5 of New York, have invented certain new and useful Improvements in Yarn Cleaners, fully described and represented in the following specification and the accompanying drawings, forming a part of the same.

10 This invention relates to yarn cleaners for eliminating impurities, such as parts of seeds, parts of stems, slubs, specks and other particles from yarn before the yarn is woven into cloth, so that a superior quality 15 of cloth may be produced from comparatively inexpensive yarns.

The invention aims to provide a simple device for removing such particles from a traveling yarn and discharging the particles 20 from the device without the use of any mechanically driven parts. Such parts I have found detrimental in yarn cleaning devices, both because they complicate the device, adding materially to the expense of in- 25 stallng it, and because they become entwined with the shreds of fibrous material which is necessarily removed from the yarn with the particles and so render the operation of the device uncertain.

30 The yarn cleaner of the present invention serves to separate particles from a traveling yarn and utilizes the pull of the yarn upon particles being separated from the yarn to eject from the cleaner particles which have 35 already been separated. This, I believe, constitutes a new principle in yarn cleaning, and it has the advantage of doing away with the necessity for any mechanically driven parts such as have heretofore been found 40 necessary in order to provide for the ejection from the cleaner of particles separated from the yarn.

The invention may be incorporated in 45 cleaners of many different forms, some of which are hereinafter specifically described.

A yarn cleaner embodying the invention may include a plurality of units each comprising means providing a long and narrow particle-guiding opening or slot located at 50 one side of the yarn and having its entrance end immediately adjacent to the yarn and its discharge end remote from, and preferably below, the line of travel of the yarn. The opening tapers inwardly from its entrance 55 end to a width less than the diameter of the yarn, but sufficient to permit longitudinal

travel of the particles along the opening under the effect of the pull of the yarn on the particles which are being separated from the yarn in the opening.

In order that the invention may clearly be understood, I will describe in detail a number of different forms of yarn cleaners, illustrated in the annexed drawings, each of which includes a plurality of cleaning units 60 providing such particle-guiding openings or slots. In the first form, illustrated in Figs. 1 to 6, inclusive, each unit provides two guiding openings, one at each side of the line of travel of the yarn, and each of these 65 openings is formed between the edges of two fixed blades. In the second and third forms, illustrated respectively in Figs. 7 to 11, inclusive, and Figs. 12 to 17, inclusive, each unit provides two guiding openings at opposite sides of the yarn, and each of these 70 openings is formed between the edge of a blade and the surface of a bed over which the yarn travels.

Fig. 1 is a side elevation of a yarn cleaner 80 of the first form;

Figs. 2, 3, 4, 5 and 6 are enlarged views of a unit of the first form, Fig. 2 being a side elevation, Fig. 3 a front elevation showing the bar sectioned on the line 3—3 of 85 Fig. 2, Fig. 4 a transverse section on the line 4—4 of Fig. 2, Fig. 5 a side view with two of the cleaning members removed, and Fig. 6 a plan view;

Fig. 7 is a side elevation of a yarn cleaner 90 of the second form;

Figs. 8, 9, 10 and 11 are enlarged views of a unit of the second form, Fig. 8 being a front elevation of the unit showing the bar sectioned on the line 8—8 of Fig. 9, Fig. 9 95 a side elevation, Fig. 10 a plan view, and Fig. 11 a transverse section on the line 11—11 of Fig. 9;

Fig. 12 is a side elevation of a yarn cleaner 100 of the third form;

Figs. 13, 14, 15 and 16 are enlarged views of a unit of the third form, Fig. 13 being a side elevation of the unit taken from the same side as Fig. 12, Fig. 14 a side elevation of the unit from the opposite side, Fig. 15 105 a transverse section on the line 15—15 of Fig. 13, and Fig. 16 a plan view; and

Fig. 17 is a side elevation taken from the opposite side from Fig. 12 and showing a modified means of adjustment.

The yarn cleaners shown in the drawings are each adapted to operate upon a traveling

yarn which is being drawn from the bobbin or other supply into a winding or spooling or other machine. Each form of cleaner is provided with a supporting frame or bar 5 which may conveniently be secured to a portion of the frame of any such machine by any desired means of attachment. It will be understood, however, that any of the yarn cleaners shown may be mounted in any 10 desired manner and will operate upon any traveling yarn regardless of the nature of the machine by which the yarn is drawn forward through the cleaner.

The first form of cleaner, illustrated in 15 Figs. 1 to 6, inclusive, comprises a bar 10, on one end of which is mounted a tension device 13 of ordinary construction. In aligned relation along one side of the bar 10 are mounted the cleaning units 15. As 20 the units are all alike, a description of one of them will suffice.

A cleaning unit 15 comprises two upper cleaning members 20, 20' and two lower cleaning members 30, 30'. The cleaning 25 member 20 comprises a supporting portion or foot 21, an outwardly bent portion 22, an outwardly flaring ear 23, and a cleaning blade 24. The cleaning member 20' is similar to the member 20 and its parts are 30 identified in the drawings by the same reference numbers as the parts of the member 20, a prime being added to each number. The lower cleaning member 30 comprises a supporting portion or foot 31 and 35 a blade 34, while the lower cleaning member 30' has a similar foot 31' and a similar blade 34'.

The four cleaning members are secured to the bar 10 by screws 16 passing through 40 their feet. A removable spacing member 17 is placed between the feet 31, 31' of the members 30, 30'.

The upper blades 24, 24' are bevelled on the outside at 25, 25' to form acute cleaning 45 edges 26, 26'. These cleaning edges are curved as indicated in Figs. 1, 2 and 5. The lower blades 34, 34' are bevelled on the outside at 35, 35' so as to form acute cleaning edges 36, 36' which are curved somewhat more sharply than the cleaning edges 26, 26'. The cleaning edges 26 and 36 lie in a common plane, and the cleaning edges 26' and 36' lie in a common plane. These 55 planes are parallel and separated by a distance determined by the thickness of the spacing member 17. The distance between the planes should be substantially equal to the diameter of the yarn, so that the planes are tangential to the yarn at opposite sides thereof. In order to adjust the unit for use in connection with yarns of different diameters, a plurality of spacing members of different thicknesses may be provided.

The cleaning edge 26 is cut away at 27 60 and the front corner 28 of the cleaning

edge 26' is turned in. Similarly the cleaning edge 36' is cut away at 37 and the front corner 38 of the cleaning edge 36 is turned in.

The edges 26 and 36 form between them an 70 opening or slot 40 which lies wholly at one side of the yarn. The slot 40 tapers inwardly from its entrance end 41 to a neck 42 of less width than the diameter of the yarn, and tapers outwardly from the neck 75 42 to its discharge end 43. The entrance end 41 of the slot 40 is immediately adjacent to the yarn A¹, while the discharge end 43 of the slot is some distance below the line of travel of the yarn. The opening 80 or slot 40' included between the edges 26' and 36' is similar to the slot 40.

In the operation of the cleaning device described, the yarn is passed around the tension device 13 and then drawn downward and forward between the ears 23, 23' of each unit until it extends in a straight horizontal line, passing between the blades 24 and 24' of each unit and between the turned-in corners 28, 38 of the blades 26' and 36 of each unit. It is then drawn continuously forward. The particles adhering to the yarn and projecting therefrom enter the slots 40, 40'. As the yarn is drawn forward, the particles pass along longitudinally in the slots 40, 40', being separated from the yarn at or about the time they reach the necks 42, 42'. The necks are, however, of such width that the particles being separated from the yarn and the particles which have been separated are moved continuously forward through the necks and the outwardly tapering portions of the slots by the pressure of the particles behind them, which is caused by the pull of the 90 yarn. The particles are, therefore, continuously discharged from the lower ends of the slots.

Certain features of the first form of cleaner illustrated in Figs. 1 to 6 form the subject matter of my divisional application filed February 9, 1924, Serial No. 691,569, and are in consequence not claimed herein.

The second form of yarn cleaner, illustrated in Figs. 7 to 11, inclusive, differs from the first form in that the two lower blades 30, 30' of that form are replaced by a bed 130 whose cleaning surface 136 is opposed to the edges of both the upper blades and is in effect a common edge cooperating with the edges of the upper blades to form the two guiding openings or slots.

The second form of cleaner comprises a bar 110 upon one end of which is mounted a tension device 113 of ordinary construction. In aligned relation on the bar 110 are mounted the cleaning units 115. As the units are all alike, a description of one of them will suffice.

A cleaning unit 115 comprises two upper cleaning members 120, 120' and a lower cleaning member or bed 130. The cleaning member 120 comprises a supporting portion 6 or foot 121, an outwardly flaring ear 123, and a cleaning blade 124. The cleaning member 120' is similar to the member 120 and its parts are identified in the drawings by the same reference numbers, a 10 prime being added to each number.

The feet 121, 121' of the upper cleaning members contain square holes which are mounted on the projecting square portion 116 of a pivot rod 117 which extends 15 through the bar 110 and is rotatably mounted in the bar. The feet are retained on the rod by a nut 118. A spring 150 is coiled around a pin 152 projecting from the bar 110 and around the square portion 116 20 of the rod 117 between the feet 121 and 121'. The spring 150 serves to spread the feet apart. The ends 153 of the spring 150 engage the rear portions of the upper cleaning members 120, 120' and tend to turn 25 these members and the pivot rod 117 in a clockwise direction (Figs. 7, 9). On the back end of the rod 117 is a collar 151 which is fixed on the rod by a set screw 154. A stop pin 155, projecting from the collar 151 and engaging the front corner of the bed 130, limits the turning of the rod 117 30 under the influence of the spring 150.

The bed 130 contains in its under side a recess 131 which is seated on the bar 110 35 and the bed is secured to the bar by means of a screw 132.

The blades 124, 124' of the upper cleaning members 120, 120' are parallel and spaced apart by a distance which may be 40 adjusted by turning the nut 118 with respect to the rod 117. The distance between the blades should be made substantially equal to the diameter of the yarn to be cleaned. The blades are bevelled on the 45 outside at 125, 125' so as to form acute cleaning edges 126, 126'. These cleaning edges are curved as indicated in Figs. 7 and 9. The cleaning surface 136 of the bed 130 lies under the cleaning edges 126, 50 126' and is curved in the same direction as these edges and somewhat more sharply.

The cleaning edge 126 is cut away at 127 and the front corner 128 of the cleaning edge 126' is turned in. The front corner 55 138 of the bed 130 extends transversely to the blades.

The cleaning edge 126 of the blade 124 forms with the cleaning surface 136 of the bed 130 an opening or slot 140 which, in 60 the operation of the device, lies wholly at one side of the yarn. The slot 140 tapers inwardly from its entrance end 141 to a neck 142 and tapers outwardly from the neck 142 to its discharge end 143. When 65 the device is in operation, the entrance end

141 of the slot 140 is immediately adjacent to the yarn, while the discharge end 143 is some distance below the line of travel of the yarn. The opening or slot 140' included between the cleaning edge 126' of 70 the blade 124' and the surface 136 of the bed 130 is similar to the slot 140.

The width of the necks of the two slots may be adjusted by loosening the set screw 75 154 and turning the collar 151 so as to vary the circumferential position of the stop pin 155 on the pivot rod 117. The position of the pin should be adjusted so that the edges 126, 126' do not touch the surface 136 of the bed, and so that the necks of the slots have a width less than the diameter of the 80 yarn to be cleaned. The exact adjustment which is most satisfactory in any case depends to some extent upon the size and quantity of particles to be removed from the yarn. It is usually desirable to make the width of the necks of the slots of the 85 units which operate upon the yarn first slightly greater than the width of the necks of the later units. 90

In the operation of the cleaner described the yarn A² is passed around the tension device 113 and then drawn downward and forward between the ears 123, 123' of each unit until it extends in a straight horizontal line passing between the blades 124 and 124' of each unit and between the turned-in corner 128 of the blade 124' and the edge 138 of the bed 130 of each unit. It is then drawn continuously forward. The particles adhering to the yarn and projecting therefrom enter the slots 140, 140'. As the 95 yarn is drawn forward the particles pass along longitudinally in the slots, being separated from the yarn at or about the time they reach the necks of the slots. The necks are, however, of such width that the particles being separated from the yarn and the particles which have been separated are 100 moved continuously forward through the necks and the outwardly tapering portions of the slots by the pressure of the particles behind them, which is caused by the pull of the yarn. The particles are, therefore, 105 continuously discharged from the lower 110 ends of the slots. 115

The third form of yarn cleaner illustrated in Figs. 12 to 16 has a supporting frame consisting of a bar 210 and a plate 211 secured to the bottom of the bar. Upon one end of the bar 210 is mounted a tension device 213 of ordinary construction. In aligned relation on the bar 210 are mounted the cleaning units 215 while an adjusting means for each unit is mounted on the plate 211. As the units and their adjusting means are all alike, a description of one of them will suffice. 120

The cleaner unit 215 of the third form is 125 in general similar to a cleaning unit of the 130

second form and comprises upper cleaning members 220, 220' having ears 223, 223', blades 224, 224', and feet 221, 221' containing square holes mounted upon the square portion 216 of a pivot rod 217 which extends through the bar 210; and a lower cleaning member or bed 230 seated on the bar 210 and secured thereto by means of a screw. As in the second form, the 10 feet 221, 221' of the upper cleaning members are spread apart and the blades 224, 224' are urged toward the bed 230 by means of a spring 250 which is coiled around a pin 252 projecting from the bar 210 and 15 around the square portion 216 of the rod 217.

The means for limiting the turning of the rod 217 and the upper cleaning members under the influence of the spring 250 differs 20 from that used in the second form. In the third form this means comprises a block 251 mounted on the back end of the rod 217 and held against turning on the rod by a set screw 254, and a screw 255 passing 25 through a tapped hole in the plate 211 and having its upper end in engagement with the block 251.

As in the second form, the cleaning surface 236 of the bed 230 is more sharply 30 curved than the portions of the cleaning edges 226, 226' of the blades 224, 224' which are opposed to this surface, so that the cleaning edges 226, 226' form with the cleaning surface 236 of the bed openings or slots 35 240, 240', each of which tapers inwardly from its entrance end 241 to a neck 242 and tapers outwardly from its neck 242 to its discharge end 243.

The blades and bed of the third form 40 differ from those of the second form in that in the third form the bed 230 is comparatively short, while the blades 224, 224' extend beyond and below the rear end of the bed and consequently beyond the discharge 45 end 243 of the slots 240, 240'. The portions 229, 229' of the blades which extend beyond and below the beds serve as deflectors to direct the particles discharged from the slots 240, 240' downwardly. These 50 deflectors 229, 229' most desirably spread apart from each other as best seen in Figs. 15 and 16, so that particles do not become lodged between them.

The width of the necks of the two slots of 55 the unit may be accurately adjusted by means of the screw 255. The screw 255 is most desirably turned so that the edges 226, 226' of the blades do not touch the surface 236 of the bed, and so that the necks of the slots 240, 240' have a width less than 60 the diameter of the yarn to be cleaned.

The operation of the third form of cleaner described is similar to that of the second form, except that the particles which are 65 continuously discharged from the discharge

ends 243 of the slots 240, 240' are not directed downwardly by the slots, but are turned downward by the deflectors 229, 229'.

In the modification of the third form shown in Fig. 17, means are provided for adjusting the widths of the slots of all the units simultaneously as well as for a separate adjustment of the slots of each individual unit. In this modification a bar 256 is slidably mounted on the plate 211 70 by means of screws 257 which pass through longitudinal slots 258 in the plate 211. The longitudinal position of the bar 256 is determined by a screw 259 which passes through a tapped hole in an upward projection 260 at one end of the plate 211 and has its end in engagement with one end of the bar 256. This end of the bar 256 is retained in engagement with the screw 259 by means of a compression spring 261 reacting between the other end of the bar 256 and another upward projection 262 on the plate 211. The bar 256 is provided with a plurality of inclined cam surfaces 263 upon which ride screws 264 passing through 80 tapped holes in the blocks 251 of the units.

It is apparent that by means of the apparatus described, the width of the slots of all the units may be adjusted simultaneously by means of the screw 259, while in addition, the width of the slots of any individual unit may be adjusted independently by means of its screw 264. It is thus possible to adjust all the units simultaneously in accordance with the diameter of the yarn to be cleaned and in accordance with the general size and quantity of specks or other particles projecting from a particular yarn, while at the same time each unit may be adjusted individually in accordance with the size and quantity of the specks which are left upon the yarn when it reaches that unit. After the proper relative adjustment of the size of the slots of the individual units has been ascertained, 100 the cleaner may be adjusted for use in connection with different yarns by merely turning the screw 259 and thus adjusting all the units simultaneously.

It should be understood that the three 110 forms of yarn cleaners which have been described are merely illustrative embodiments of the invention and that the invention is by no means limited to these particular forms.

It should be noted that since during the operation of the cleaner no relative motion takes place between the edges which form the guiding slots, the members providing these edges may, if desired, be formed integral with each other. It is, however, more desirable to use separate members in order to provide for adjustment of the width of the neck of the slot.

I am aware that the yarn cleaners have 130

heretofore been made with means providing a V-shaped gripping slot which tapers to a point or to a width so small that the particles drawn into the slot are gripped in it and that such yarn cleaners have been provided with means for intermittently discharging the gripped particles. I make no claim to yarn cleaners of this character.

What I claim is:

- 10 1. A yarn cleaner for removing particles adhering to a traveling yarn, comprising means providing a slot whose width is fixed during the operation of the cleaner, said slot being located at one side of the yarn and 15 formed to engage particles projecting from the yarn, to guide said particles away from the yarn at an acute angle to its direction of travel, and to discharge them continuously.
- 20 2. A yarn cleaner for removing particles adhering to a traveling yarn, comprising means providing a slot whose width is fixed during the operation of a cleaner, said slot extending in the general direction of the 25 travel of the yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 30 under the effect of the pull of the yarn upon particles entering the slot, the portion of the slot whose width is less than the diameter of the yarn being located wholly at one side of the yarn, and means for retaining said cleaning members in fixed relation to each other during the operation of the cleaner.
- 35 3. A yarn cleaner for removing particles adhering to a traveling yarn, comprising means providing opposed edges which are spaced apart, are held in fixed relation to each other during the operation of the cleaner, and form a guiding slot extending in the general direction of the travel of the 40 yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 45 under the effect of the pull of the yarn upon particles entering the slot, the portion of the slot whose width is less than the diameter of the yarn being located wholly at one side of the yarn, means for adjustably varying the relative position of said cleaning members to adjust the minimum width of the slot, and means for retaining said members in fixed relation to each other during the 50 operation of the cleaner.
- 40 4. A yarn cleaner for removing particles adhering to a traveling yarn, comprising means providing opposed edges which are spaced apart, are held in fixed relation to each other during the operation of the cleaner, and form a guiding slot extending in the general direction of the travel of the 45 yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 50 under the effect of the pull of the yarn upon particles entering the slot, the portion of the slot whose width is less than the diameter of the yarn being located wholly at one side of the yarn.
- 45 5. A yarn cleaner for removing particles adhering to a traveling yarn, comprising a cleaning member having an acute edge, a second cleaning member spaced from said edge and forming therewith a guiding slot 55 extending in the general direction of the travel of the yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 60 under the effect of the pull of the yarn upon particles entering the slot, the portion of the slot whose width is less than the diameter of the yarn being located wholly at one side of the yarn.
- 60 6. A yarn cleaner for removing particles adhering to a traveling yarn, comprising a cleaning member having an acute edge, a second cleaning member spaced from said edge and forming therewith a guiding slot 65 extending in the general direction of the travel of the yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 70 under the effect of the pull of the yarn upon particles entering the slot, the portion of the slot whose width is less than the diameter of the yarn being located wholly at one side of the yarn, and means for retaining said cleaning members in fixed relation to each other during the operation of the cleaner.
- 70 7. A yarn cleaner for removing particles adhering to a traveling yarn, comprising means providing opposed edges which are spaced apart, are held in fixed relation to each other during the operation of the cleaner, and form a guiding slot extending in the general direction of the travel of the 75 yarn but diverging from the line of travel of the yarn so that its entrance end is immediately adjacent to the yarn and its discharge end is remote from the yarn, and tapering inwardly from its entrance end to a minimum width less than the diameter of the yarn, but sufficient to permit longitudinal travel of the particles in the slot 80 under the effect of the pull of the yarn upon particles entering the slot, the portion of the slot whose width is less than the diameter of the yarn being located wholly at one side of the yarn, means for adjustably varying the relative position of said cleaning members to adjust the minimum width of the slot, and means for retaining said members in fixed relation to each other during the 85 operation of the cleaner.
- 80 8. A yarn cleaner as claimed in claim 7, in which the opposed edges are so positioned that the entire guiding slot is wholly at one side of the yarn.
- 85 9. A yarn cleaner as claimed in claim 7 in which the opposed edges lie in a common plane tangential to the yarn.

10. A yarn cleaner for removing particles from a traveling yarn, comprising a member having an acute edge, and a second member spaced from said edge and forming there-
5 with a guiding slot extending in the general direction of the travel of the yarn but diverging from the line of travel of the yarn so that its entrance end is immediately adjacent to the yarn and its discharge end 10 is remote from the yarn, and tapering inwardly from its entrance end to a neck of less width than the diameter of the yarn, and tapering outwardly from said neck toward its discharge end, the portion of the slot 15 whose width is less than the diameter of the yarn being located wholly at one side of the yarn, and means for retaining said members in fixed relation to each other during the operation of the cleaner.
- 20 11. A yarn cleaner for removing particles from a traveling yarn, comprising a member having an acute edge, and a second member spaced from said edge and forming there-
25 with a guiding slot extending in the general direction of the travel of the yarn but diverging from the line of travel of the yarn so that its entrance end is immediately adjacent to the yarn and its discharge end is 30 remote from the yarn, and tapering inwardly from its entrance end to a neck of less width than the diameter of the yarn, and tapering outwardly from said neck toward its discharge end, the portion of the slot 35 whose width is less than the diameter of the yarn being located wholly at one side of the yarn, means for adjustably varying the relative position of said members so as to adjust the width of the neck of the slot, and means for retaining said members in 40 fixed relation to each other during the operation of the cleaner.
12. In a cleaning unit for use with a traveling yarn, the combination of a bed over which the yarn passes, said bed being provided with a surface which diverges from the line of travel of said yarn, a blade at one side of the yarn provided with an edge opposed to and spaced from said bed and arranged so as to form with the bed a guiding slot tapering inwardly to a width less than 45 the diameter of the yarn, but sufficient to permit longitudinal movement in the slot of particles removed from the yarn under the pull of the yarn upon particles entering the slot, and means for retaining said blade in fixed relation to said bed during the operation of the cleaner.
13. In a cleaning unit for use with a traveling yarn, the combination of a bed provided with a surface which diverges from the line of travel of said yarn, a blade provided with an edge opposed to and spaced from said bed and arranged to form with the bed a guiding slot tapering inwardly 50 from one end to a neck of less diameter than
- the yarn and tapering outwardly from said neck toward its other end, means for retaining said blade in fixed relation to said bed during the operation of the cleaner, and means for positioning said yarn upon said bed adjacent to said slot.
14. In a cleaning unit for use with a traveling yarn, the combination of a bed provided with a surface which diverges from the line of travel of said yarn, a blade provided with an edge opposed to and spaced from said bed and arranged to form with the bed a guiding slot tapering inwardly from one end to a neck and outwardly from said neck toward its other end, means for retaining said blade in fixed relation to said bed during the operation of the cleaner, means for adjustably varying the position of said blade with respect to said bed to adjust the width of the neck of the slot, and means for positioning said yarn upon said bed adjacent to said slot.
15. A yarn cleaner for removing particles adhering to a traveling yarn, comprising a plurality of cleaning units positioned to operate upon the yarn in series and each comprising two cleaning members forming between them an elongated guiding slot at one side of the yarn having its entrance end immediately adjacent to the yarn and its discharge end remote from the yarn and tapering inwardly from its entrance end to a neck and outwardly from said neck toward its discharge end, and means for simultaneously varying the relative position of the cleaning members of each unit so as to adjust the width of the neck of the guiding slot of each unit.
16. A yarn cleaner for use with a traveling yarn, comprising the combination of a bed having a surface over which the yarn passes, a blade at one side of the yarn provided with an edge opposed to said surface of the bed and inclined thereto, resilient means tending to urge said blade and bed towards each other, and means other than the opposed edge and surface of said blade and bed arranged continuously to receive the thrust of said resilient means so as to retain said edge and surface in spaced relation to each other.
17. In a cleaning unit for use with a traveling yarn, the combination of a bed provided with a surface which diverges from the line of travel of the yarn, a blade provided with an edge opposed to and spaced from said bed and arranged to form with the bed a guiding slot tapering inwardly from one end to a neck and outwardly from said neck toward its other end, resilient means tending to urge said blade toward said bed, and a stop limiting the movement of the blade under said resilient means and adjustable to vary the width of the neck of the slot.
18. A yarn cleaner for use with a travel-

ing yarn, comprising a plurality of cleaning units positioned to operate upon the yarn in series and each comprising the combination of a bed with a surface which diverges from the line of travel of the yarn and a blade provided with an edge opposed to and spaced from said bed and arranged to form with the bed a guiding slot tapering inwardly from one end to a neck and outwardly from said neck toward its other end, and means for simultaneously varying the position of the blade of each unit with respect to the bed of that unit to adjust the width of the necks of the slots of all the units.

19. A yarn cleaner for use with a traveling yarn, comprising a plurality of cleaning units positioned to operate upon the yarn in series and each comprising the combination 20 of a bed with a surface which diverges from the line of travel of the yarn, a pair of blades each provided with an edge opposed to and spaced from said bed and arranged so as to form therewith a guiding slot tapering inwardly from said slot to a neck and outwardly from said neck toward its other end, resilient means for urging said blades toward said bed, a plurality of stops, one

positioned to limit the movement of the blades of each unit, and means for simultaneously moving all of said stops so as to adjust the widths of the necks of the slots of all the units.

20. A yarn cleaner for use with a traveling yarn, comprising a supporting frame, a plurality of beds mounted in aligned relation on said frame and each having a surface which diverges from the line of travel of the yarn, a plurality of pivot rods turnably mounted on said frame, a plurality of pairs of blades, each pair being mounted on one of said pivot rods and having cleaning edges opposed to one of the beds, resilient means tending to turn said pivot rod so as to urge each pair of blades toward one of the beds, means for limiting the turning of each pivot rod comprising an eccentric stop member mounted on each pivot rod and a bar mounted on the frame and providing a plurality of cam surfaces, one engaging 45 each of said eccentric stops, and means for adjusting said bar longitudinally of the frame.

In testimony whereof I have hereunto set my hand.

HENRY E. VAN NESS.
